INSECT SCREEN FOR AUTOMOBILES

Leslie D. O'Donnell, Benkelman, Nebr.

Application May 7, 1956, Serial No. 41,387

Term of patent 14 years

(Cl. D14—18)

Fig. 1 is a front view of an insect screen for automobiles, showing my new design;

Fig. 2 is a top view thereof; and

Fig. 3 is an end view thereof.

A rear view of the screen would present an appearance similar to that of Fig. 1.

I claim:

The ornamental design for an insect screen for automobiles, as shown and described.
